UNITED STATES PATENT OFFICE.

GUSTAF ALBIN NILSON, OF CHICAGO, ILLINOIS.

PLUMBING SYSTEM.

1,201,081.

Specification of Letters Patent. Patented Oct. 10, 1916.

Application filed June 2, 1916. Serial No. 101,924.

To all whom it may concern:

Be it known that I, GUSTAF ALBIN NILSON, a citizen of the United States, and resident of Chicago, county of Cook, and State of Illinois, have invented certain new and useful Improvements in Plumbing Systems, of which the following is a specification, and which are illustrated in the accompanying drawings, forming a part thereof.

10 The invention relates to plumbing, and contemplates certain improvements upon the plumbing system as shown in Patent No. 993,095, issued to me on May 23, 1911.

15 The object of the invention is to facilitate the installation of plumbing in buildings, and to this end the invention proposes the use of certain improved fittings which are adapted for adjustable connection with the plumbing fixtures.

20 A feature of the invention permits of a confinement of the connections which are extended through the floors within a reduced depth whereby the installation of the plumbing in buildings which have floors of 25 reduced thickness, such as concrete buildings, is accomplished without the extension of any part of the plumbing under the ceiling of a lower floor.

In the accompanying drawings, Figure 1 is a side elevation, partly in section showing an arrangement of the plumbing for connection with the bath room fixtures in a building comprising a plurality of floors, Figs. 2 and 3 are detail perspective views 30 showing certain of the fittings employed in the plumbing system illustrated in Fig. 1, Fig. 4 is a central transverse sectional view of another fitting, Fig. 5 is a detail plan view of the plumbing system partly in section, Fig. 6 is a sectional view showing the manner in which the wash basin may be connected with the plumbing system, Figs. 7 and 8 are detail perspective views showing the drain connections for the bath tub, 40 Fig. 9 is a sectional view taken on the line 9—9 of Fig. 5, and Fig. 10 is similar to Fig. 5, but shows a form of construction which may be used when two bath rooms are located upon opposite sides of a common intermediate wall.

In carrying out the invention an upright stack or main waste pipe 15, is extended through the building from the basement to the roof. This stack is of usual construction, except that an upwardly inclined branch, as 16, is provided adjacent each of

the floors of the building. Similarly, a main vent pipe 17 is provided and this main vent pipe extends, as usual, from the lowest floor upon which fixtures are provided to a connection, as 18, with the stack 15, which is above the so-called water level.

In the simple form of construction illustrated in Fig. 1, each of the branches 16 of the main waste pipe 17, is formed with an inclined nipple 19, and an upwardly facing hub or nipple 20. The nipple 19 serves for receiving the end of a drain pipe 21, which drain pipe is in turn connected with both the lavatory, indicated at 22, Fig. 5, and the bath tub, as 23. As shown, the drain pipe 21 extends in nearly a horizontal direction at substantially the floor level and is formed with two receiving hubs 24 and 24^a. The bath tub drain pipe 26 is preferably connected with the hub 24 and continues in the same direction with the drain pipe 21. The lavatory drain pipe 25, on the other hand, is vertical, and is connected with the hub 24^a. The closet drain, as 27, is connected with the upwardly facing hub or nipple 20 of the waste pipe branch 16.

Separate vent connections 28, 29 and 30 are provided for the closet 31, the lavatory 22 and the bath tub 23 respectively. The lavatory connection is illustrated in detail in Figs. 4 and 6. It preferably includes a fitting 32, having aligned nipples 33 and 36 at its top and bottom and an offset downwardly facing discharge arm 34. The discharge arm 34 of the fitting 32 is connected with the drain pipe 25. The nipple 33 at the top of the fitting 32, on the other hand, receives the lower end of the vent connection 29. An elbow 35 is connected with the remaining nipple, as 36, of the fitting 32, and the drain, as 37, from the lavatory bowl 22, is connected with the elbow 35. The use of the elbow 35, and its connection with the lower end of the fitting 32, permits of a wide range of angular adjustment in the lavatory drain 37. The length of the lavatory drain 37 is further rendered adjustably by mounting a bushing 38 in the end of the elbow 35 for telescopically receiving the inner end of the drain 37, in a well known manner.

The bath tub drain pipe 26 and vent connection 30 are preferably entered in two of the sockets 39, 40, of a 3-arm fitting 41. The third socket, as 42, of the fitting serves for receiving one end of an elbow 43. The other

- 2
- end of the elbow 43 is connected with a clean-out drum 46, at one side, as through a nipple 44, which is formed on the side of the drum adjacent its lower end. In event the 5 bath tub 23 is located at some distance from the wall (not shown), a length of pipe 45, will be extended between the elbow 43 and the nipple 44. A second nipple 47, preferably formed upon the side of the drum 46 adjacent its lower end, serves for receiving the drain connection, as 48, from the bath tub 23.
- The use of the elbow 43 and its connection with the socket 42, permits of the drum 46 being located at any convenient place upon the bath room floor, as 49. Furthermore, the 10 location of both of the nipples 44 and 47 upon the side of the drum 46 permits of the fittings being confined within a depth which 15 is not greater than the thickness of the floor, even though the floor may be of reduced thickness, as when made of concrete. It will be understood that the drum 46 has the usual removable cover 50, and that this cover is 20 exposed upon the bath room floor, where it is readily accessible. It will be noted, however, that the elbow 43 and the receiving bend, as 51 of the drain 48, form a trap, 25 whereby the chamber of the drum 46 is always filled with water to a level which is 30 above the nipples 44 and 47. There is accordingly no possibility for the escape of sewer gas from the drum 46 into the room, even upon removal of the cover 50. The 35 location of the nipples 44 and 47 upon the sides of the drum 46, also provide for the introduction of a cleaning rod through the drum into the parts which are connected with either of said nipples.
- 40 The closet drain preferably comprises the stem 27 of an integral T-shaped fitting formed with an upturned receiving bend 52 at that end which is remote from the T-head, as 53, of the fitting. As shown, the two arms 45 of the T-head 53 are of different size, the lower arm 54 being the larger, and being designed for connection with the upwardly facing nipple 20, of the waste pipe branch 16. The other arm, as 55, is preferably of reduced size, and is made in the form of a 50 socket for receiving the lower end of the closet vent connection 28. The provision of the upwardly facing nipple 20 on the waste pipe branch 16, and the formation of the two arms 54, 55, of the T-head 53 in axial alignment, permit of the closet drain 27 being turned to any angle. It is accordingly unnecessary for the length of the closet drain 27 to correspond with the distance at which 55 the closet is located from the wall. It is merely necessary to so locate the stack 15 that the closet drain 27 may be turned to the proper angle for causing the receiving bend 52 of the drain 27 to register with the closet outlet.

In both the lower and intermediate floors of a building, the vent connections 28 and 29, lead to the main vent pipe 17 through a branch vent pipe 56. In the intermediate floors of the building, the vent connection 30, 70 also extends to the branch vent pipe 56. In the lower floor of the building, the main vent pipe 17 may be directly connected with the fitting 41. In the top floor of the building all of the vent connections 28, 29 and 30 75 may extend to a horizontal portion of the main vent pipe 17.

While both threaded and calked joints are shown upon the drawing, it will be understood that the several fittings may be constructed for the use of either of these forms of joint, as desired, except that where the rotation of the fitting is inconvenient, a pipe, as 29, which has a threaded connection at one end, will preferably be connected to the 80 corresponding fitting at the other end by means of a calked joint.

When two bath rooms are to be located upon the same floor, the form of construction illustrated in Fig. 10, may be employed. 90 The construction here illustrated is the same as that already described, except that fittings 57 and 58, each having two receiving inlets, as 59, 60 or 61, 62, are employed in place of the fittings 32 and 41, respectively. Furthermore the waste pipe branch 16 is formed with two upwardly facing hubs or nipples 63 and 64. When the hubs 63 and 64 are used, the two closets may be aligned upon opposite sides of the wall, as 65, by inclining the two 100 closet drains 27, as shown.

I claim as my invention, —

1. In a plumbing system, in combination, a waste pipe, a vent pipe, an integral fitting having aligned oppositely facing nipples at 105 its top and bottom and a lateral discharge nipple intermediate its ends, connection between the nipple at the top of the fitting and the vent pipe, an elbow having swiveled connection with the nipple at the bottom 110 of the fitting, connection between the said lateral discharge nipple of the fitting and the waste pipe and a drain leading from a bath room fixture connected with the said elbow.

2. In a plumbing system, in combination, a waste pipe, a vent pipe; an integral fitting having aligned oppositely facing nipples at 115 its top and bottom and a lateral discharge nipple intermediate its ends, the last mentioned nipple being substantially at the floor level, connection between the nipple at the top of the fitting and the vent pipe, connection between the said lateral discharge nipple of the fitting and the waste pipe, an 120 upright drum having a removable cover, the top of the drum being above the level of the lower margin of the said discharge nipple of the fitting and the bottom of the drum being below the level of the nipple at the 125 130

bottom of the fitting, an elbow connecting with the nipple at the bottom of the fitting and with the side of the said drum adjacent its lower end, a drain pipe connecting with 5 the side of the said drum adjacent its lower end and a receiving upward bend at the outer end of the said drain pipe.

3. A bath tub drain comprising, in combination, an upright drum having a removable cover and a pair of lateral nipples adjacent its lower end, pipes having upward bends for receiving and discharge, connected with the nipples of the drum, the top of the drum being above the level of the highest 10 part of the said upward bend of the discharge pipe and a vent pipe connected with the discharge pipe at its said upward bend.

4. A bath tub drain comprising, in combination, a chambered fitting having a removable cover, receiving and discharge pipes connecting with the fitting below the cover, the discharge pipe extending upwardly from its point of connection with the fitting but not to the level of the top of the fitting and 15 a vent pipe connected with the discharge pipe at its highest part.

5. In a plumbing system, in combination, a stack, a branch waste pipe connecting with the stack intermediate its ends, an upwardly 20 facing hub formed on the branch waste pipe, a horizontally disposed T-shaped fitting having one of its arms seated in the said hub, a vent pipe connected with the other arm of the said T-shaped fitting and an up- 25 turned receiving bend at the end of the T-shaped fitting.

6. In a plumbing system, in combination, a stack, a branch waste pipe connecting with the stack intermediate its ends, an upwardly 30 facing hub formed on the branch waste pipe, a horizontally disposed T-shaped fitting 35

having one of its arms seated in the said hub, and a vent pipe connected with the other arm of the said T-shaped fitting, the stem of the T-shaped fitting serving as a 45 drain for a bathroom fixture or the like.

7. In a plumbing system, in combination, an integral chambered fitting having aligned oppositely facing nipples at its top and bottom, and a discharge nipple communicating 50 with the chamber of the fitting at one side of the line of the two first mentioned nipples, a vent pipe connected with the nipple at the top of the fitting, a waste pipe connected with the said discharge nipple of the fitting, 55 an elbow connected with the remaining nipple of the fitting and a drain leading from a bath room fixture or the like connected with the said elbow.

8. In a plumbing system, in combination, 60 a stack, a branch waste pipe connecting with the stack intermediate its ends, two hubs formed on the branch waste pipe, one of the said hubs facing upwardly, a horizontally disposed T-shaped fitting having one of its 65 arms seated in the upwardly facing hub, the stem of the T-shaped fitting serving as a drain for a bath room fixture or the like, a vent pipe connected with the other arm of the said T-shaped fitting, and a drain for 70 another bath room fixture connected with the other one of said hubs.

9. In a plumbing system, in combination, a stack, an upwardly facing receiving hub formed on the stack, a horizontally disposed 75 T-shaped fitting having one of its arms seated in the said hub, the stem of the T-shaped fitting serving as a drain for a bath room fixture or the like and a vent pipe connected with the other arm of the said T- 80 shaped fitting.

GUSTAF ALBIN NILSON.
